UNITED STATES PATENT OFFICE

MERLIN CLYDE LOVE, OF PHOENIX, ARIZONA

VAPORIZER

Application filed October 20, 1928. Serial No. 313,857.

The present invention relates to improvements in carbureting devices for internal combustion engines and has for its primary object to provide a vaporizer for positively and efficiently vaporizing the gasoline or other fuel prior to the admixture of the same with air and previous to the discharge of the fuel into the intake manifold.

One of the important objects of the present invention is to provide a vaporizer which includes a sectional exhaust manifold structure, a partition being arranged within the exhaust manifold to divide the same into inner or outer communicating compartments, the inner compartment being adapted to have communication with the exhaust port of the internal combustion engine to receive exhaust gases therefrom, a coiled pipe section being arranged within the outer chamber for communication at one end with a fuel supply pipe, the other end being adapted to have communication with a vaporized fuel outlet pipe that enters the intake manifold, whereby the fuel will be subjected to the exhaust gases entering the outer chamber from the inner chamber of the manifold to effect the vaporization of the fuel prior to its discharge into the intake manifold, where the same co-mingles with fresh air.

A further object is to provide a vaporizer of the above mentioned character which includes means for thermostatically controlling the vaporization of the fuel in the coiled pipe arranged in the outer chamber of the exhaust manifold, said means being at all times efficient and reliable in its operation.

Still a further object is to provide a vaporizer of the above mentioned character which includes manually operable means for controlling the supply of the vaporized fuel to the intake manifold, thereby preventing unnecessary waste of the fuel.

A further object is to provide a vaporizer of the above mentioned character which is simple in construction, inexpensive, strong and durable, and further well adapted to the purpose for which it is designed.

Other objects of the invention will become apparent as the nature of the invention pro-

ceeds, and when taken in connection with the accompanying drawings.

In the accompanying drawings:

Figure 1 is a side elevation of an internal combustion engine, showing my improved vaporizer attached thereto.

Figure 2 is a longitudinal sectional view, through the exhaust manifold, showing the normal position of the slide valves.

Figure 3 is a side elevation of the exhaust manifold, the outer section thereof being removed to more clearly illustrate the slide valves and the actuating means therefor.

Figure 4 is a sectional view, taken approximately on the line 4—4 of Figure 3.

Figure 5 is a similar section, taken substantially upon the line 5—5 of Figure 3.

Figure 6 is a sectional view, taken on the line 6—6 of Figure 2.

Figure 7 is a detail perspective view of 70 one of the slide valve units.

In the drawings, wherein for the purpose of illustration is shown the preferred embodiment of my invention, the numeral 1 designates generally an internal combustion engine, with which is associated an intake manifold 2, the vertical leg portion 3 of which is flared at its open lower end to provide an air inlet. My improved vaporizer further includes the provision of a sectional exhaust manifold unit, which is denoted generally by the reference character 4. This exhaust manifold unit extends longitudinally along one side of the engine block, and is supported thereon by the attaching brackets 5. A partition 6 is arranged within the manifold 4, for dividing the same into the inner or outer compartments or chambers 7 and 8 respectively, the outer chamber 8 being open at its inner side.

The sections of the exhaust manifold are detachably secured together by the bolts 9 so that the inner open side of the outer chamber has its edges abutting the partition 6.

The outer or rear side of the inner chambers 7 is formed with a series of exhaust gas inlet nipples 10, that afford communication between the respective cylinders of the internal combustion engine 1 and the inner chamber 7 of the exhaust manifold 4, to admit the 100

exhaust gases from the engine to said inner chamber 7.

As is more clearly illustrated in Figures 4 and 5 of the drawings, the inner chamber is 5 of rectangular shape in cross section, while the outer chamber 8 is of oval design. An exhaust pipe 11 extends from the rear end of the outer chamber 8 for discharging the exhaust gases from the exhaust manifold after 10 the same has been utilized for the purpose of vaporizing the fuel that passes through a coiled pipe 12 that is arranged longitudinally within the intermediate portion of the outer chamber 8, as shown in Figure 2.

15 The forward end of the coiled pipe section 12 is formed with a laterally disposed nipple 13 that extends through an opening formed in the outer side of the chamber 8, and the outer end portion of the nipple is threaded 20 for receiving thereon a suitable coupling 14 that affords a means for connecting the forward end of the fuel supply pipe 15 with the laterally disposed nipple associated with the forward end of the coiled pipe section 12, the 25 other end of said supply pipe having communication with a gasoline tank (not shown).

The rear end of the coiled pipe section 12 is provided with a similar nipple 16 that extends through the outer side of the rear end 30 portion of the chamber 8 and a vaporized fuel delivery pipe 17 is connected, at its rear end to the nipple 16, while the forward end of this delivery pipe extends into the intake manifold 2, at the juncture of the vertical leg 35 portion 3 with the horizontal arm portion of said intake manifold, as clearly shown in Figure 1. The forward end of the vaporized fuel delivery pipe 17 may be constructed to provide a spray nozzle for discharging the vaporized fuel in the intake manifold in the intake manifold, in a fine spray so that the same may become more effectively atomized with the fresh air that is sucked to the manifold 2 during the operation of the engine 1.

45 A valve 18 of any conventional construction is arranged in the delivery pipe 17 for regulating the flow or supply of the vaporized fuel to the intake manifold and this valve is controlled from a remote point through the 50 medium of the actuating rod 19 as also disclosed very clearly in Figure 1. The rod 19 preferably extends within easy access of the operator of the vehicle.

As is clearly disclosed in Figure 2, the 55 partition 6 that extends longitudinally and vertically in the exhaust manifold 4 is formed at its respective ends with the exhaust gas outlet openings 20 and 21 respectively, the coiled pipe section 12 being located between 60 these openings. These openings afford communication between the inner and outer chambers and for the purpose of controlling the vaporization of the fuel that passes through the coiled pipe section 12, I have 65 provided a thermostatically operated device,

the construction of which will now be specifically described.

A substantially rectangular shaped slide valve 22 is arranged for slidable movement within the chamber 8, across the forward 70 opening 20 and suitable guides 23 are provided for cooperation with the slide valve 22, the rear face of this slide valve having sliding engagement with the front face of the partition 6. A tubular stem 24 extends horizontally from the rear end of the slide valve 22.

A similar slide valve 25 is arranged for slidable movement within the rear end portion of the chamber 8 across the opening 21, 80 guides 26, similar to the guides 23 being provided for cooperation with the slide valve 25.

A tubular stem 27 extends horizontally from the forward end of the slide valve 25. These slide valves are operatively connected 85 together for simultaneous operation through the medium of a connecting rod 28, the ends thereof being adjustably secured within the respective hollow stems 24 and 27, by suitable set screws 29.

The control means for the sliding valves further includes the provision of a thermostatic link element 30 that is made of such material as to be very sensitive to heat and cold, and which will readily expand and contract. 95 One end of this thermostatic link element 30 is fixedly secured within the chamber 8, as at 31, while the other end of this link is pivotally connected to the lower end of a lever 32, which lever is pivoted adjacent its lower end to the front side of the partition 6, as at 33, with reference more particularly to Figures 2 and 3 of the drawings. The upper end of the lever 32 is pivotally connected to the upper end of the arm 34, that extends upwardly 100 from the rod 28.

The operation of my improved vaporizer may be briefly stated as follows:

Normally the valves 22 and 25 are arranged in the position shown in Figure 2, whereby 110 the port 20 is uncovered and the port 21 is covered.

The exhaust gases will pass into the chamber 7 from the internal combustion engine through the inlet 10 and will be caused to 115 travel forwardly in the chamber 7 and will enter the forward end of the outer chamber 8 through the port 20. The exhaust gases entering the outer chamber 8 will travel rearwardly and will completely envelop the 120 coiled pipe section 12, through which the fuel passes, so as to effect the vaporization of the fuel in the pipe section 12, prior to the same being discharged into the delivery pipe 17. The exhaust gases will then pass out through 125 the exhaust pipe 11, and through the conventional muffler (not shown) into the atmosphere. In this manner, the fuel will be thoroughly vaporized before being admitted into the intake manifold, and when delivered to 130

the intake manifold, the same will become atomized with the fresh air that is sucked upwardly through the vertical leg portion 3 so that the proper charge will be delivered to the 5 internal combustion engine cylinders.

As the exhaust manifold becomes heated, the link 30 will expand, causing the actuation of the lever 32, whereby to operate the slide valves 22 and 25 simultaneously, in such a 10 manner as to move the valve 22 over the port 20 and simultaneously uncovering the port 21.

In this manner, the exhaust gases entering the chamber 7 will leave through the port 21 and will be discharged into the exhaust pipe 15 11, without being caused to circulate around the coiled pipe section 12.

In this manner, the degree of vaporization of the fuel that is caused to flow through the coil pipe section 12 will be regulated. As 20 heretofore mentioned, the valve 18 may be actuated by the operator of the vehicle to regulate the supply of the vaporized fuel to the intake manifold and when the motor is not running, the valve 18 is closed, thereby preventing the waste of fuel. 25

It will thus be seen from the foregoing description, that I have provided a carbureting device or vaporizer that can be readily and easily installed on an internal combustion engine without necessitating much alteration, and furthermore a vaporizer of this character will, at all times, be efficient and reliable in operation.

The use of a vaporizer of the above mentioned character will reduce the fuel consumption necessary to operate the engine and furthermore, by admixing a highly vaporized fuel with fresh air, the efficiency of the operation of the engine will be increased.

While I have shown the preferred embodiment of my invention, it is to be understood that various changes in the size, shape and arrangement of parts may be resorted to, without departing from the spirit of the invention or the scope of the appended claims.

What is claimed is:

1. A vaporizer for internal combustion engines comprising in combination, an exhaust manifold, an intake manifold provided with an air inlet at its lower end, a partition dividing the exhaust manifold into inner and outer communicating chambers, the inner chamber being provided with inlet ports to receive the exhaust gases from the engine, an 55 exhaust discharge pipe extending from the outer chamber, a coiled pipe section arranged within the outer chamber, a fuel supply pipe having communication with the forward end of the coiled pipe section, a vaporized fuel delivery pipe affording communication between the rear end of the coiled pipe section and the intake manifold, said coiled pipe section being adapted to be heated by the exhaust gases entering the outer chamber, a 65 valve arranged in the vaporized fuel deliv-

ery pipe for regulating the flow of the fuel to the intake manifold, and a thermostatically operated means for controlling the vaporization of the fuel passing through the coil pipe section, said last mentioned means comprising a slide valve arranged in each end of the outer chamber, the partition being formed with exhaust gas openings in the ends thereof, a rod connecting the slide valves together for simultaneous operation, one of said exhaust gas openings being closed by its respective slide valve, while the other exhaust gas opening in the partition is uncovered, and a thermostatic element arranged within the outer chamber and operatively connected with the rod to effect the sliding movement thereof to uncover the first mentioned exhaust opening and simultaneously cover the second mentioned exhaust opening in the partition. 70 75 80 85

2. A vaporizer for internal combustion engines comprising in combination, an exhaust manifold, an intake manifold provided with a fresh air inlet at its lower end, a partition arranged within the exhaust manifold for dividing the same into inner and outer chambers, said partition being formed with exhaust gas openings at the respective ends thereof, an exhaust gas discharge pipe extending from the rear end of the outer chamber, said inner chamber adapted for communication with the exhaust ports of an internal combustion engine for receiving the exhaust gases therefrom, a coiled pipe section arranged within the outer chamber between said exhaust openings in the partition, a fuel supply pipe having connection with the forward end of the coil pipe section, a vaporized fuel delivery pipe providing communication between the rear end of the intake manifold and coil pipe section, a valve arranged in the vaporized fuel delivery pipe for regulating the flow of the vaporized fuel to said intake manifold, a slide valve for each of the openings in the partition, a rod operatively connecting the slide valves together, one of the exhaust openings in the partition being opened when the other opening in the partition is closed to effect the discharge of the exhaust gases from the forward end of the inner chamber into the forward end of the outer chamber, whereby to cause said exhaust gases to circulate around the coil pipe section, entering the exhaust gas discharge pipe, and thermostatically operated means for automatically closing the front exhaust gas opening in the partition and uncovering the rear opening of the partition, for the purpose described. 90 95 100 105 110 115 120

In testimony whereof I affix my signature. 125
MERLIN C. LOVE.
